(57) **CLAIM**

The ornamental design for a chandelier, as shown and described.

DESCRIPTION

FIG. 1 is a perspective view of a chandelier; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is an enlarged view of portion 8 shown in FIG. 1. The dot-dash broken lines represent boundaries of the enlarged portions and form no part of the claimed design. The evenly spaced broken lines illustrate portions of the chandelier that form no part of the claimed design.

1 Claim, 8 Drawing Sheets
